Primary Examiner — Clint A Samuel(74) *Attorney, Agent, or Firm* — Alston & Bird LLP(57) **CLAIM**

The ornamental design for a lighting device, as shown and described.

DESCRIPTION

FIG. 1 is a top front perspective view of a lighting device according to the present design.

FIG. 2 is a bottom rear perspective view of the lighting device of FIG. 1;

FIG. 3 is a front view the lighting device of FIG. 1;

FIG. 4 is a back view of the lighting device of FIG. 1;

FIG. 5 is a left side view of the lighting device of FIG. 1;

FIG. 6 is a right side view of the lighting device of FIG. 1;

FIG. 7 is a top view of the lighting device of FIG. 1; and,

FIG. 8 is a bottom view of the lighting device of FIG. 1.

The broken lines are directed to unclaimed features of the lighting device and form no part of the claimed design.

1 Claim, 8 Drawing Sheets(56)
